UNITED STATES PATENT OFFICE.

JOSEPH F. MUHEIM, OF WARREN, MASSACHUSETTS.

DOFFING APPARATUS FOR SPINNING-MACHINES.

SPECIFICATION forming part of Letters Patent No. 761,980, dated June 7, 1904.

Application filed January 28, 1904. Serial No. 190,980. (No model.)

To all whom it may concern:

Be it known that I, JOSEPH F. MUHEIM, a citizen of the United States, residing in Warren, in the county of Worcester and State of Massachusetts, have invented certain new and useful Improvements in Doffing Apparatus for Spinning-Machines, of which the following is a specification.

This invention relates to a new and improved apparatus for doffing the bobbins in spinning-machines, whereby all the bobbins may be simultaneously doffed by a simple operation on the part of the attendant in an economical and efficient manner, all as fully described below and illustrated in the accompanying drawings, in which—

Figure 1 is an elevation of a portion of a spinning-machine provided with my doffing attachment. Fig. 1^A is a plan of a portion of the same. Figs. 2, 3, and 4 are sections taken on line *x*, Fig. 1, looking toward the left. Fig. 5 is a section taken on line *y*, Fig. 1, looking toward the right. Fig. 6 is a plan in enlarged detail, illustrating the clips for holding, removing, and applying the bobbins. Fig. 7 is an elevation in enlarged detail of the same.

Similar characters of reference indicate corresponding parts.

1 represents the frame of the machine, 2 being the lower rail and 3 the spindle-rail, and 4 represents the full bobbins and 5 the empty bobbins, all constructed as usual.

6 represents a shaft (see Figs. 1 and 4 and dotted lines in Fig. 2) supported by the lower rail and adapted to be operated by a crank 7 or other suitable device. On this shaft is a worm 8 in engagement with the gear-wheel 9 on a shaft 10, supported in the frame. Rigid on this shaft 10 are two cams 11 and 12.

40 The periphery of the cam 11 engages a cone-shaped roll 13, Figs. 1, 2, 3, and 5, supported by a lever 14, whose hub 15 is rigid on the rocker-shaft 16. Rigid on this shaft 16 is the lever 17, whose lower end is pivoted to the link 18, whose lower end is pivoted to the arm 19, adjustably connected with the lever 20, one end of which is loose on the shaft 10 and the other end is pivotally connected with the link 21, pivoted at its opposite end to the doffer-

bar 22. This doffer-bar extends through a swinging guide 23, whose lower end is pivoted at 24 to the bracket 25, secured to the rail 2, and whose upper end embraces at 26 the doffer-bar.

The cam 12 engages the roll 27, Fig. 4, supported by one end of the elbow-lever 28, pivotally supported at 29 by the extension 30 of the bracket 25, the opposite end of said lever being pivotally connected with one end of the substantially U-shaped lever 31, the opposite end of which is hinged at 32 to the guide 23.

There are a number of the lifting mechanisms above described—that is to say, mechanisms between and including the rocker-shafts 16 and the doffer-bars 22—although but one is illustrated in Fig. 1, all of said mechanisms being supported by the rocker-shafts 16, and the links 21 in said mechanisms being constructed exactly the same as the link 21 (illustrated in the drawings) and being adapted to be applied to the rod 33 in the same manner as illustrated in the drawings, whereby said rod constitutes a pivotal connection between a plurality of links and lifting mechanisms. Instead, however, of applying both cams to each rocker-shaft the rocker-shafts are each connected by a rigid arm 34, slotted at 35, with an arm 36, rigid on a bar 37, supported by and sliding endwise in the frame. By this means all the rocker-shafts act simultaneously without necessarily applying a cam 11 to every rocker-shaft.

The upper ends of the doffer-bars 22 support a horizontal shaft 38, provided on its upper side with the longitudinal groove 39, containing a slide 40. (See Figs. 1^A, 6, and 7.) Rigidly secured to the opposite sides of this shaft 38 and extending horizontally therefrom are the full bobbins 4 and the empty bobbins 5, the full bobbins being on one side and the empty bobbins being on the other side and the full and empty bobbins being alternately arranged, as indicated in Fig. 1^A. The full bobbins are supported by clips, each of which comprises a rigid jaw 41, a movable jaw 42, pivoted to the rigid jaw at 43 by means of inwardly-extending plates 44, constituting a hinge, a flange or plate 45, integral with

the jaw 41 and bolted to the bar 38 at 46, and the curved arm 47, which is integral with the movable jaw 42 and extends to the groove 39 and across the path of the projections 48, 5 Figs. 1^a, 6, and 7, which extend up from the slide 40 in said groove, the purpose of which is below described. These jaws 41 and 42 are formed at their outer ends into the curved grapples 49, each of which is preferably bifurcated, as shown in Fig. 7. A spring 50 is bolted at 51 to the plate 47 and bears against the movable jaw 42, and a hook 52 extends from the movable jaw beyond and over the edge of the stationary jaw 41, thus limiting the extent of 10 the closing of said jaws by the action of the spring 50 when the bobbin is removed. To the opposite side of the bar 38 are bolted clips 53, which are provided at their outer ends with spring-grapples 54 of substantially the 15 shape of the grapples 49. The clips 41, 42 are for holding the full bobbins 4, and the clips 53 are for holding the empty bobbins 5, said sets of clips not only projecting from opposite sides of the bar 38, but those of one set 20 being arranged alternately with those of the other set.

The shaft 38 is provided at one end, Figs. 1 and 2; with a roll 55, and at its other end it has mounted on it a gear-wheel 56. The roller 30 is for engagement with a cam 57, secured to and extending inwardly from the left side of the frame. 58 is a rack extending downward from the opposite side of the frame. (See Figs. 1 and 5.) 59 represents the spindles on the spindle- 35 rail 3. 60 represents a counterbalance on the arm 61, extending from the rocker-shaft 16.

In Figs. 1 and 2 the machine may be considered to be in its normal position, with full bobbins ready to be removed and replaced by 40 empty bobbins. The operation of the parts is as follows: By turning the crank 7 the shaft 6 is rotated, thus imparting rotation by means of the worm 8 to the gear-wheel 9, and hence to the shaft 10 and to the cam 12 thereon. 45 This cam engages the roll 27, thus swinging up the long arm of the elbow-lever 28, whose short arm swings in and draws with it the lever 31, which, being pivoted at 32 to the guide 23, swings said guide inward, and hence swings 50 inward the doffer-bar 22. The cam 11, being also rotated by the shaft 10, then moves the roller 13 and through the lever 14 imparts rotation to the rocker-shaft 16, said shaft by means of the lever 17, link 18, and arm 19 lifting the 55 lever 20, whose outer end lifts the link 21, and hence the doffer-bar 22, the swinging in of the doffer-bar by means of the cam 12 and the lifting thereof by means of the cam 11 bringing said bar and the shaft 38 into the position indicated in Fig. 3—that is to say, opposite the middle of the full bobbin with the jaws 49 of the clip embracing and holding said bobbin, said jaws being pressed against the opposite sides of the bobbin by means of the spring 50. 60 The mechanism being now in the position in-

dicated in Fig. 3 the cam 11 through the above-described mechanism intermediate thereof and the shaft 38 lifts still higher the clip 41 42 until the bobbin held thereby is held entirely off the spindle in the position indicated 70 in Fig. 4. At the same time the roller 55 at one end of the shaft 38 is engaged by the cam 57, and said shaft moves endwise until the gear-wheel 56 is brought into engagement with the rack 58. The cam 11 next operates 75 through the above-described mechanism with the effect of lowering the doffer-bar and causing the gear-wheel to rotate sufficiently to impart a half-rotation to the shaft 38 in the manner indicated in Fig. 5, the endwise movement 80 of the shaft 38 having during this process brought full bobbins between the spindles 59 and the empty bobbins opposite the spindles, as shown in Fig. 1^a. When the half-rotation of the gear 56 and the shaft 38 is completed, 85 therefore, the empty bobbins have been swung over and upon the spindles from which the full bobbins were removed. When the empty bobbins have been deposited on the spindles, the gear-wheel has been dropped below the 90 rack. The cam 12 then operates to release the empty bobbins from the clips 53 by swinging the doffer-bar 22 outward, leaving them on the spindles. The slide 40 is then moved in the groove, thus by means of its projections 48 engaging the finger 47 of each said clip (which is holding the full bobbin) and releasing it.

The above description is of the operation of a single mechanism applied to a single bobbin, 100 All the bobbins, however, are operated at the same time, a sufficient number of exactly similar mechanisms being provided for the purpose, this statement being subject only to the provision above described and embodied in 105 the parts 34, 36, and 37. To start again and apply empty bobbins, the shaft 38 must be given a half-rotation in order to bring the clips for the reception of the empty bobbins on the outside. It is also necessary that the 110 shaft 38 should be brought back endwise into its original or normal position in order that it may be again engaged by the cam 57 when it is lifted to a suitable height. When the gear 56 was in engagement with the rack, a spring- 115 pin 62 was held by the spring 63 into the annular groove 64, (illustrated in Fig. 1,) said spring-pin being supported by a suitable bracket 65. A spring 66, secured at its opposite ends to the doffer-bar 22 and to the eye 120 of a ring 67 on the shaft 38, holds said shaft normally to the left. Hence in order to release the shaft and allow it to return to its normal position the handle 68 on the spring-bolt 62 is pressed down, thus withdrawing the 125 bolt from the annular groove 64 and allowing the spring 66 to return the shaft to its original position.

I do not confine myself to the locking and releasing mechanism 62 to 67 nor to the en- 130

gaging slide 40, provided with the projections 48, as other mechanisms may be employed in place of these devices, if desired.

Having thus fully described my invention, 5 what I claim, and desire to secure by Letters Patent, is—

1. In a doffing apparatus for spinning-machines, an actuating-shaft mounted in the frame; a cam mounted on a suitable shaft; 10 mechanism intermediate of the actuating-shaft and the cam for imparting rotation to the latter; a rocker-shaft supported by the frame; mechanism intermediate of the cam and rocker-shaft for imparting movement to the latter; a swinging doffer-bar; and mechanism intermediate of the said cam and doffer-bar whereby said doffer-bar is lifted to a point substantially opposite a loaded bobbin, for the purpose set forth.
2. In a doffing apparatus for spinning-machines, an actuating-shaft mounted in the frame; a cam mounted on a suitable shaft; 15 mechanism intermediate of the actuating-shaft and the cam for imparting rotation to the latter; a swinging doffer-bar; and mechanism intermediate of the said cam and doffer-bar whereby the doffer-bar is swung inward into engagement with a loaded bobbin, for the purpose set forth.
3. In a doffing apparatus for spinning-machines, a cam-shaft and a pair of cams mounted thereon and adapted to operate successively; a swinging doffer-bar; mechanism intermediate of one cam and the doffer-bar for lifting said bar; mechanism intermediate of the other cam and doffer-bar; and a bobbin-engaging device supported by the doffer-bar, 20 whereby the doffer-bar is first lifted by one cam to the height of a loaded bobbin, and then 25 swung inward by the other cam until said engaging device grasps and holds said bobbin, for the purpose set forth.

4. In a doffing apparatus for spinning-machines, a cam-shaft and a pair of cams mounted thereon; a swinging doffer-bar; mechanism intermediate of said cams and the doffer-bar whereby said bar is lifted to the height of a loaded bobbin and swung inward to said bobbin; mechanism supported by the doffer-bar for engaging said bobbin; and mechanism adapted to lift the bobbin from its spindle after it has been grasped by the engaging device supported by the doffer-bar, for the purpose set forth.

5. In a doffing apparatus for spinning-machines, a cam-shaft and a pair of cams mounted thereon; a swinging doffer-bar; mechanism intermediate of said cams and the doffer-bar whereby said bar is lifted to the height of a loaded bobbin and swung inward toward said bobbin; a bobbin-engaging device supported by the doffer-bar; mechanism adapted to lift the bobbin from its spindle after it has been grasped by said engaging device; mechanism 60 for moving the engaged bobbin horizontally;

and mechanism for releasing said bobbin, for the purpose set forth.

6. In a doffing apparatus for spinning-machines, the actuating-shaft 6, shaft 10 and worm-gear intermediate of said shafts; the 70 cam 11 rigid on shaft 10; the rocker-shaft 16 and lever 14 rigid thereon, said lever being provided with the cam-roll 13; the lever 17 rigid on the shaft 16; the link 18; the lever 20 pivotally connected at one end with the 75 shaft 10; the arm 19 connecting said lever 20 with the link 18; the doffer-bar 22; the swinging guide 23 in engagement with said doffer-bar; the link 21 connecting the doffer-bar with the lever 20; and the shaft 38 provided with 80 clips for engaging the loaded and empty bobbins, for the purpose set forth.

7. In a doffing apparatus for spinning-machines, the actuating-shaft 6, shaft 10, and worm-gear intermediate of said shafts; the 85 cam 12 rigid on the shaft 10; the elbow-lever 28 provided at one end with a cam-roll; the substantially U-shaped lever 30 pivotally connected to the elbow-lever; the doffer-bar 22; the swinging guide 23 in engagement with said 90 doffer-bar and pivotally connected with the U-shaped lever; and the shaft 38 provided with clips for engaging the loaded and empty bobbins, for the purpose set forth.

8. In a doffing apparatus for spinning-machines, the shaft 10; the cams 11 and 12 rigid on said shaft; a plurality of rocker-shafts 16; mechanism intermediate of the cam 11 and one of the rocker-shafts for actuating said rocker-shaft; the arms 34 rigid on the rocker-shafts; the horizontal bar 37 supported by and sliding endwise in the frame, and pivotally connected with the upper ends of the arms; a plurality of doffer-bar guides 23 pivoted to the frame; the doffer-bars in engagement with 105 said guides; the horizontal rod 33 connecting and acting as a pivot for the doffer-bars; mechanisms intermediate of the rocker-shafts and the doffer-bars, for lifting said doffer-bars; and mechanisms intermediate of the cams 12 110 and the doffer-bar guides, for swinging said doffer-bars, substantially as described.

9. In a doffing apparatus for spinning-machines, the bar 38 provided with the horizontal groove 39; a slide in said groove provided with projections extending up therefrom; the clips each consisting of the stationary jaw 41, 49, the movable jaw 42, 49, a hinged connection between said jaws, the hook 52 extending from one jaw to the other, and the curved arm 120 47 extending from the movable jaw over said groove; and the springs 50 holding the rear ends of the jaws normally apart, for the purpose set forth.

10. In a doffing apparatus for spinning-machines, the bar 38 provided with oppositely-extending rows of clips, one row being adapted to grasp full bobbins and the other being adapted to grasp empty bobbins; the cam 57 secured to the machine; mechanism for lifting 130

said bar into engagement with the cam; a gear-wheel rigid on the bar; and the rack secured to the frame and adapted to be brought into engagement with the wheel by the cam and 5 thereby impart rotation to said bar, for the purpose set forth.

In testimony whereof I have signed my name

to this specification in the presence of two subscribing witnesses.
